T. E. WALKER,
WINDOW CONSTRUCTION,
APPLICATION FILED APR. 25, 1921.

1,428,068.

Patented Sept. 5, 1922.

UNITED STATES PATENT OFFICE.

THOMAS E. WALKER, OF DETROIT, MICHIGAN, ASSIGNOR TO CRITTAL CASEMENT WINDOW CO., OF DETROIT, MICHIGAN, A CORPORATION OF MICHIGAN.

WINDOW CONSTRUCTION.

Application filed April 25, 1921. Serial No. 464,303.

To all whom it may concern:

Be it known that I, THOMAS E. WALKER, a citizen of the United States of America, residing at Detroit, in the county of Wayne 5 and State of Michigan, have invented certain new and useful Improvements in Window Constructions, of which the following is a specification, reference being had therein to the accompanying drawings.

10 This invention relates to windows having frames with sashes swingable therein, and more particularly to that type of window frame in which transversely hinged supported edges of sashes constantly remain in 15 the plane of the window frame with the hinge edges of the sashes adjustable in the frame so that the sashes may be swung outwardly and lowered for ventilating and cleaning purposes. My invention has further reference to the above type of window 20 wherein superposed sashes have interlocking or interengaging meeting rails with said rails constructed so that the upper sash of the window may be locked in a closed position 25 by the lower sash, particularly when the sashes are fully within the window frame. As the window sashes are ordinarily made of metal, adjustment of the upper sash, from an open to a closed position, 30 may not at all times place the upper sash in position to be locked closed by the lower sash. In other words, it often occurs that the upper sash is not fully closed and consequently the upper sash may foul or remain 35 unlocked by the closed lower sash, or the upper sash must be further manipulated to permit of the lower sash locking it in a closed position.

The primary object of my invention is to 40 furnish a window, as characterized above, with means for automatically and fully closing or placing an upper sash within a frame so that it may be locked in a closed position by the lower sash, said means being actuated by the lower sash to correctly position 45 the upper sash so that portions thereof may be engaged and held by the meeting rail of the lower sash.

Another object of my invention is to provide 50 a window with shiftable cam members operable in synchronism with one sash, to fully seat and close an adjacent sash, and said shiftable cam members are housed within the window frame and obviate the ne-

cessity of using exterior devices for such 55 purposes.

A further object of this invention is to provide a transverse slidable sash-supporting member composed of parts, two of which are standard for sashes or frames of various widths, and the remaining part of the transverse sash supporting member may be made in various lengths so that a transverse sash supporting member may be quickly constructed for various sizes of casement 60 windows.

The above and other objects are attained by a construction that has been put into practice and will now be described by aid of the drawing, wherein—

70 Figure 1 is an enlarged vertical cross sectional view of a portion of the window frame, showing the meeting rails of the upper and lower sashes, with the meeting rail of the upper sash about to be actuated by the lower sash, so that said sashes may assume a closed locked position within the window frame;

75 Fig. 2 is a similar view showing the sashes completely closed;

Fig. 3 is a horizontal sectional view taken on the line III—III of Fig. 2;

Fig. 4 is a perspective view of a portion of the window, showing one of the shiftable cam members;

80 Fig. 5 is a front elevation of a portion of a window, and

Fig. 6 is an elevation of a transverse member in accordance with this invention.

85 In describing my invention by aid of the fragmentary views above referred to, I desire to point out that some of the parts to be hereinafter described are duplicates, as the present illustration simply shows one side of a window as having a channel frame 90 or stile 1 with an upper sash 2 and a lower sash 3 adjustable relative to each other and also relative to the frame. In the particular type of window to which my invention refers, the upper sash 2 has its upper rail 95 hingedly supported so that the sash may be swung outwardly and the upper hinged rail of the sash lowered within the window frame. The upper sash 2 has a meeting rail 100 4 which has a cross sectional shape providing an inner short leg 5 and an outer long leg 6 and the short leg will be again specifically referred to.

The lower sash 3 is supported somewhat similar to the upper sash 2, that is, so that it may be swung outwardly relative to the window frame and the supporting rail of 5 said sash raised and lowered in the window frame. The supporting rail of the lower sash 3 is known as the meeting rail, and is designated 7. The cross sectional shape of this meeting rail provides, among other 10 things, an inner long leg 8 which is adapted to overlie the short leg 5 of the upper sash 2 when said sashes are closed.

The meeting rail 7 of the lower sash 3 is provided with hinge members 9 preferably 15 at the ends of said meeting rail, and said hinge members may be connected to the meeting rail by screws or other fastening means. The hinge members 9 are employed to hingedly connect the meeting rail 7 to a 20 transverse member which is constantly within the casement frame and has its ends slideable in the rails or stiles 1. The transverse member, as best shown in Fig. 6, is preferably composed of an intermediate portion 25 10 and end portions 11, said end portions being standard for sashes and frames of various widths, and the intermediate portion may be made of various lengths so as to provide a transverse member of a desired 30 length or width. This structural feature however, is optional with the maker of the window.

The end portions 11 of the transverse member are formed to receive the barrel 35 portions of the hinge members 9, and said hinge members are hingedly or pivotally connected to the end portions 11 by pintles 12 mounted endwise within the end portions 11, thus providing hinges fashioned after 40 piano hinges.

Each end portion 11 has a vertically disposed shoe 13 extending above and below the transverse member and the shoe is adapted to slide in the frame or stile 1. As best 45 shown in Figs. 3 and 4, the frame or stile 1 may be provided with a channel wear member or liner 14 and the outer face of the shoe 13 may be provided with an adjustable or 50 fixed wear plate or contact piece 15. That portion of the shoe 13 which extends above the transverse member is provided with an outwardly projecting cam member or inclined way 16 having a comparatively sharp upper end 17 adapted to impinge against 55 the short leg 5 of the upper meeting rail 4, at the end of said short leg, and cause the partially closed upper sash to fully close so that the meeting rail 7 of the lower sash 3 may properly approach the meeting rail 4 60 and cause the short leg 5 thereof to be sandwiched between the long leg 8 of the meeting rail 7 and the transverse member which will be enclosed as the meeting rails 4 and 7 are brought together.

65 With this type of window the upper sash

4 is first swung to a closed position or approximately so, and then the lower sash 3 is closed causing the cam members to be elevated and impinge against the short leg 5 of the meeting rail 4, at the ends of said 70 meeting rail. This takes place providing the upper sash 2 has not been completely closed, otherwise, the meeting rail 7 approaches the meeting rail 4 and the two rails assume positions about the transverse 75 member. If the upper sash 2 is not completely closed the cam members 16 will deflect or wedge the meeting rail 4 inwardly and as the upper sash assumes proper alignment with the channels 1, the long leg 8 and 80 the transverse member of the lower sash 3 ride into position, as shown in Fig. 2 to retain the meeting rail 4 in a closed position and against outward movement until the meeting rail 7 has been lowered. It is obvious that the bottom rail or edge of the 85 lower sash 3 may be locked to secure both sashes within the window frame.

By reference to Fig. 3 it will be noted that the cam members 16 are enclosed by 90 the frame and the channeled side rails of the upper sash 2 when said sash is closed, and since the transverse member is also rendered invisible by the closed sashes, the window frame and sash construction, in its entirety, will present a finished and neat appearance.

What I claim is:—

1. In a window, wherein upper and lower sashes are disconnected and independently 100 tilttable and the lower sash holds the upper sash closed when said sashes are in alignment, the combination of a member adapted to support the lower sash, and means carried by said member adapted to contact with 105 the upper sash to cause the upper sash to align with the lower sash so as to be held closed thereby.

2. The combination covered by claim 1, wherein a portion of the upper sash is sandwiched between said member and a portion of the lower sash.

3. In a window frame, the combination of a movable lower sash adapted to have its upper edge move up and down in the window frame, an upper sash supported in said window frame and adapted to have its lower edge swung in an arc, and a cam member at the upper edge of said lower sash actuated by said sash to move upwardly against the 115 lower edge of said upper sash and cause said upper sash to swing into vertical alignment with said lower sash.

4. The combination called for in claim 3, wherein there is a cam member at each side 125 of the window frame with said cam members disposed to be concealed when the sashes are closed.

5. As a new article of manufacture for a window having sashes, a piece of hardware 130

adapted to slide in the window to support one sash, said piece of hardware having cams at its ends adapted to impinge against the other sash and effect adjustment of said 5 sash.

6. In a window, a frame having independently adjustable swingable sashes with meeting rails adapted to be brought together so that one meeting rail may hold the other 10 closed, cam members at the ends of one meeting rail to engage the ends of the other meeting rail and cause the last mentioned meeting rail to be deflected into the path of the first mentioned meeting rail to be engaged and held closed thereby.

7. In a window, a transverse sash supporting member having end portions slideable in said frame, said end portions being 20 standard for frames of various widths, and an intermediate portion connecting the end portions of said member and having a length to properly space the end portions of said member to engage said frame.

8. In a window, an upper sash, a lower

sash and a transverse member supporting 25 said lower sash and having end portions shaped to slide in said frame and engage said upper sash, for the purpose herein specified.

9. A window as in claim 8, characterized 30 by the lower sash being hingedly connected to the transverse member.

10. A window as in claim 8, characterized by said upper and lower sashes having meeting rails which enclose said transverse mem- 35 ber when said sashes are closed.

11. As a new article of manufacture for a window having sashes, a piece of hardware adapted to slide, in the window to support one sash and by its sliding movement 40 contact with and effect adjustment of the other sash.

In testimony whereof I affix my signature in presence of two witnesses.

THOMAS E. WALKER.
